UNITED STATES PATENT OFFICE.

WILLIAM T. McDOWELL, OF ST. LOUIS, MISSOURI.

MATCH-RECEPTACLE.

No. 918,079.

Specification of Letters Patent. Patented April 13, 1909.

Application filed September 14, 1908. Serial No. 452,978.

To all whom it may concern:

Be it known that I, WILLIAM T. McDOWELL, a citizen of the United States, residing at the city of St. Louis, State of Missouri, have invented certain new and useful Improvements in Match-Receptacles, of which the following is a specification, reference being had therein to the accompanying drawings.

10 This invention consists in a match receptacle which is particularly well adapted to hold matches in small quantities, and which is of such size as to be conveniently carried in the pocket, or dispensed from a coin-controlled device, or adapted to be distributed gratuitously for advertising purposes.

In the drawings forming part of this specification, in which like numbers of reference denote like parts wherever they occur, Fig. 1 is a perspective view of the blank out of which the match receptacle is to be formed; Fig. 2 is a perspective view of the blank partly folded; Fig. 3 is a similar view of the blank folded in a slightly different manner, so that the entire match will be covered; Fig. 4 is a front elevation of the complete receptacle with the upper end folded as in Fig. 2, the ends of the matches being thus exposed; Fig. 5 is a front elevation of the complete receptacle with the upper end folded as in Fig. 3, the matches being covered; Fig. 6 is a side elevation of the receptacle when folded as in Fig. 4; Fig. 7 is a side elevation of the receptacle when folded as in Fig. 5; Fig. 8 is a perspective view of a modified form; and Figs. 9 and 10 are side elevations thereof, on an enlarged scale.

This match receptacle is formed out of a blank that has been cut, preferably at a single operation, by a die from any suitable material, usually cardboard, fairly stiff paper, celluloid, or the like. When the blank has been cut, it is scored or creased at 1, 2, 3, 4, 5, 6, 7, and 8. The tongue 9 is folded at the scoring 1, and lies flat against the body 10 of the blank. The loose end of the tongue 9 preferably does not reach all the way to scoring 6, but falls short thereof a distance equal to about the length of the head of a match. The matches 11 are laid upon the tongue 9, being placed with all the heads adjacent to the scoring 6. Because the heads of the matches are a little larger than the match sticks, it is necessary that they be accommodated in a space between

the body or back 10 and the flap 12. Such a space is provided by the foreshortening of tongue 9. The wings 13 are turned toward each other by folding at the scorings 2 and 3 and 4 and 5, the ends of the infolded wings 13 overlapping each other a short distance. The flap 12 is folded at the scorings 6 and 7, and brought over the infolded arms or wings 13. The lip 14, formed by folding the blank at scoring 8, is tucked under the upper edges of the infolded wings 13. The scorings 2 and 3, 4 and 5, and 6 and 7 are made at such a distance from each other, respectively, that when the folding is completed a box is formed of the appropriate interior dimensions to retain the matches in place. The lip 14 acts somewhat in the nature of a spring, and presses tightly against the matches 11, with the result that, even though the match receptacle be turned upside down, the matches will not fall out.

The depth of the box which forms the match safe proper is not so great as the length of a match, and, therefore, the matches extend out of and above said box, and the visible portions of the match-sticks or bodies rest against the upper and outside portion of tongue 9.

If any particular user of this match receptacle should prefer to have the matches completely covered when in the safe, the safe can be formed by folding the blank in a different way from that described above. The wings 13 may be folded first, then the flap 12 brought up and folded over the infolded wings 13, and the lip 14 tucked under the upper edges of the infolded wings 13. The matches may then be slipped into the box or pocket thus formed, and the tongue 9 folded at the scoring 1, and pushed down inside between the matches and the lip 14. When the receptacle is made in this form, so that the full lengths of the matches are covered, it is not necessary that all the heads of the matches be turned down, but the matches may be put in without regard to whether all the heads are up, or all of them down, or some of them up and some down. This form of the receptacle makes it necessary for the user, when he desires to remove a match from the safe, to pull out the tongue 9, and to slip it in again when he is through taking matches from the safe. The form first described is preferable, however, under some circumstances, because, by putting the heads of the matches down, the matches are safely

protected from undesired ignition and from moisture, and all the user has to do when he wants a match is to draw it out of its place, without the delay and inconvenience of pulling out and slipping back the tongue 9.

In the modification shown in Figs. 8, 9, and 10 of the drawings, provision is made in the construction of tongue 9 for use either in the manner hereinbefore described or, by 10 tearing off the part 15 below the row of perforations 16, leaving a relatively short flap which can overlap the matches and be inserted between same and the lip 14. The end of the tongue 9 may be scored as at 18 (Fig. 8) 15 when light material is used, and, by folding the end 19 at scoring 18, somewhat greater thickness is provided at the end of tongue 9, which provides the necessary space for the heads of the matches. This additional fold 20 is, however, preferably used only when the receptacle is composed of comparatively thin material, because it is usually unnecessary when stiff cardboard or thick paper or like material is used, as they possess the thickness 25 necessary to form the space for the accommodation of the match heads.

An ignition surface 17 is located either on the face of tongue 9 visible above the box or at the point indicated in Fig. 8, and may be 30 composed of roughened tin, or the like, or of sand, powdered emery, carborundum, or some chemical composition, which is caused to adhere thereto.

Having thus described my said invention, 35 what I claim and desire to secure by Letters-Patent is:

1. A match receptacle comprising a body portion, side wings carried by said body portion and arranged to overlap at their free 40 ends, a flap at one end of said body portion, a lip carried by said flap, said flap engaging said overlapped wings on their outer faces, and said lip extending over the inner ends of said wings and engaging same on their rear 45 faces, and a tongue at the opposite end of the body portion arranged to engage between said body portion and said wings.

2. A match receptacle composed of a body portion, wings carried by said body portion 50 to form the front and sides of a match containing portion in conjunction with said body portion, a tongue carried by said body portion, a detachable member borne by said tongue, a flap carried by said body portion, and a resilient element borne by said flap to 55 press against the matches and thereby retain same in place, said member being designed to form one wall of a match head receiving compartment, and when detached enabling 60 said tongue to be used as a closure for the receptacle.

3. A match receptacle composed of a body portion, a plurality of foldable members carried by the body portion for forming the 65 receptacle in conjunction with said body por-

tion, a resilient member borne by one of said members to engage the matches and to retain the same in position, and a member borne by a second of said members to form one wall of a match head receiving compartment. 70

4. A match receptacle composed of a body portion, a tongue, a thickening member borne by the tongue to form one wall of a match head receiving compartment, side wings on the body portion to form the front 75 and side walls of the receptacle, a flap on the body portion forming the bottom wall of the receptacle, and a resilient lip carried by the flap to engage on the interior of the receptacle and press against the matches to hold 80 same in position.

5. A match receptacle composed of a body portion, and means secured to said body portion to form a match receptacle in conjunction therewith, said means including a flap 85 having an extension to resiliently press against the matches and a tongue having a foldable extension to form one wall of the match head receiving compartment.

6. A match receptacle comprising a body 90 portion, wings carried by said body portion so as to overlap one another, a tongue carried by one end of said body portion, a flap carried by the other end of said body portion, and combined means to secure said flap to 95 said wings and to resiliently engage the matches at points between said wings and body portion.

7. A match receptacle composed of a body portion, wings carried by said body portion, 100 a flap at one end of said body portion, and a lip carried by said flap to engage over said wings and extend on the inner face of said wings to resiliently press against the matches.

8. A match receptacle composed of a body 105 portion, wings on the side of the body portion, a flap at one end of said body portion engaging the wings, and a tongue carried by said body portion, the free end of said tongue being folded over upon itself and extending 110 on the inner face of said body portion to points in proximity to the lower end of said body portion to form one wall of a compartment to receive the match heads.

9. A match receptacle comprising a body 115 portion, wings on the body portion arranged to extend transversely thereacross, a flap at one end of said body and a tongue at the other end of said body, and means carried by the free ends of said flap and tongue to extend inwardly in the space between said wings and the inner face of said body one of said means engaging against the front faces of the matches and the other of said means engaging against the rear faces thereof, 120 whereby the matches are retained in position.

10. A match receptacle composed of a body portion, wings on the body arranged to extend across the inner face thereof, a flap carried by the body to engage said wings,

means on the flap to resiliently engage the matches, and a tongue carried by the body and forming a continuation thereof which is bent over to engage between the inner face 5 of the body and the rear faces of the matches, said tongue on its outer face being provided with an abrasive surface.

11. A match receptacle composed of a body portion, wings on the body portion extending across the inner face thereof, a flap carried by the body arranged to engage the wings, and a tongue carried by the body, said tongue having its free end doubled over on itself and adjacent said doubled over portion 15 being formed with a row of perforations, whereby said doubled over end may be removed to permit of varying uses of the tongue.

12. In combination with a match receptacle, a tongue therefor provided with detachable means whereby said means when attached provides one wall of a match receiving compartment for the heads of the matches and whereby when said means is detached

said tongue may be employed as a closure 25 for said receptacle.

13. In combination with a match receptacle, means having a detachable part whereby when said means with said part attached is disposed on the interior of the receptacle same forms one wall of a match head receiving compartment for the matches, and whereby when said part is detached may be employed as a closure for the receptacle.

14. A match receptacle composed of a body portion, side wings carried by the body portion and extending across the inner face thereof, a flap carried by the body and engaging said wings, said flap having its free end turned over and extending downwardly 40 on the inner faces of the wings to secure the latter in position.

In testimony whereof I have affixed my signature in presence of two witnesses.

WILLIAM T. McDOWELL.
